CLOTHES HANGER

Filed June 23, 1927

UNITED STATES PATENT OFFICE.

HOMER B. EDWARDS, OF LEAD, SOUTH DAKOTA.

CLOTHES HANGER.

Application filed June 23, 1927. Serial No. 200,966.

This invention relates to clothes hangers and more particularly to a device of this character for use indoors as, for example, upon the walls of a kitchen.

8 An important object of the invention is to produce a device of this character having means for supporting a plurality of arms, so that they may be lowered to enable the clothes to be readily applied to the arms and subsequently raised to a point where they are out 10 of the way and not liable to contact with persons moving about the room.

15 A further object of the invention is to provide a novel and improved means for supporting and shifting the arms and for holding the support in its adjusted positions.

These and other objects I attain by the construction shown in the accompanying drawing, wherein for the purpose of illustration 20 is shown a preferred embodiment of my invention and wherein:—

Figure 1 is a front elevation of a clothes hanger constructed in accordance with my invention showing in dotted lines the lowered 25 position of the support;

Figure 2 is a vertical sectional view therethrough, the lower support being shown in use;

Figure 3 is an enlarged sectional view showing 30 the manner in which the handle cooperates with the lower support taken on the line 3—3 of Figure 1;

Figure 4 is a section on the line 4—4 of 35 Figure 1.

Referring now more particularly to the drawing, the numeral 10 generally designates a channel member adapted to be secured with its base against the wall or other vertical support and having at the ends of the arms 11 40 thereof inwardly directed flanges 12 opposing the base in spaced relation thereto.

The numeral 13 designates a second channel member adapted for slidable mounting in the first named member with its base opposed to the slot formed between adjacent ends of the flanges 12. The channel member 13 has secured thereto at its upper end upon its inner face a member 14 combining with the base of the channel to produce an open- 50 topped socket 15, for a purpose presently to appear. The front or base wall of the channel member 13 at its upper end has a notch 16 aligning with this socket.

Adjacent its lower end, the base of the 55 channel member 13 has secured thereto a handle 17 in the form of a piece of spring

steel bent to substantially C-form and having one end thereof permanently secured to the channel member 13, as indicated at 18. The opposite end of the strip is extended 60 through an opening 19 formed in the wall of the channel and is provided with a latch lug having a downwardly facing horizontal shoulder 20 and an upwardly facing cam face 21. Secured to the base of the channel member 10 in alignment with the space between adjacent edges of the flanges 12 is a combined bracket and stop 22 consisting of a plate having at its upper and lower ends horizontal flanges 23 extending outwardly from the base 70 of the channel. These flanges have formed therein openings 24, for a purpose presently to appear, and their outer edges are adapted to be engaged by the latch lug of the handle 17. If the channel member 13 is moving 75 downwardly at the time of engagement of the latch lug, the shoulder 20 will engage the flanges 23 and check downward movement of the channel member 13 until the latch lug is swung outwardly against the resiliency of 80 the handle to escape the same. If the channel member is moving upwardly, the cam face 21 engages against the flanges, so that the latch lug merely rides thereover.

In combination with a structure such as above described, I employ supporting arm structures such as illustrated in Figures 1 and 3. These arm structures each comprise a standard 25, the upper end of which is offset, as at 26, and has mounted thereon spaced 85 washers 27. Between these washers are disposed an arm or arms 28 for supporting the clothes. The upper washer may be retained in position by a nut threaded upon the upper end of the offset 26, as indicated at 29. The standard 25 may be engaged either in the socket 15 or in the openings 24 of the flanges 23. When engaged in the socket 15, the connection 30 between the standard and its offset seats in the notch 16 to hold the standard 90 95 in proper alignment.

When the member 13 is released for downward movement, by manipulation of the latch, the lower end of the member 14 will come into engagement with the upper flange 105 23 of the bracket 22 to limit this downward movement. While in this position, a standard 25 engaged therein will be disposed at the proper height to enable convenient application of clothes to the arm or arms supported thereby. When the clothes have been applied to the arm, the channel member may 110

be elevated through the handle 17 until this standard and the supported clothes are at the upper limit of their movement when the latch shoulder 20 will prevent downward movement of the channel member 13 and support them in this position. If desired, a standard may be engaged in the openings 24 by simply elevating the channel member 13 until the flanges 23 are exposed, as indicated in Figure 2.

Since the construction hereinbefore set forth is capable of a certain range of change and modification without materially departing from the spirit of the invention, I do not limit myself to such specific structure except as hereinafter claimed.

I claim:—

1. In combination, a vertically extending member having a channel, a support 20 slideable in the channel and having at its upper end a socket, a standard for engagement in the socket and having arms and means for securing the support in adjusted positions in the standard including a handle through which the support may be vertically adjusted, said handle comprising a resilient strip bent in C-form and having one end thereof secured to the support and the opposite end extended through an opening formed in the support 25 and into the channel, the last named end having a latch lug thereon, the channel member having upon the base of the channel stop flanges for engagement with the latch lug.

2. In combination, a vertically extending member having a channel, a support slideable in the channel and having at its upper end a socket, a standard for engagement in the

socket and having arms and means for securing the support in adjusted positions in the standard including a handle through which the support may be vertically adjusted, said handle comprising a resilient strip bent in C-form and having one end thereof secured to the support and the opposite end extended through an opening formed in the support and into the channel, the last named end having a latch lug thereon, the channel member having upon the base of the channel stop flanges for engagement with the latch lug, said flanges being perforated to receive 50 said standard.

3. In combination, a vertically extending member having a channel, a support slideable in the channel and having at its upper end a socket, a standard for engagement in the 55 socket and having arms and means for securing the support in adjusted positions in the standard including a handle through which the support may be vertically adjusted, said handle comprising a resilient strip bent in C-form and having one end thereof secured to the support and the opposite end extended through an opening formed in the support and into the channel, the last named end having a latch lug thereon, the channel member 60 having upon the base of the channel stop flanges for engagement with the latch lug, the lower end of said socket engaging the uppermost of said flanges to positively limit downward movement of the support in the 65 channel member.

In testimony whereof I hereunto affix my signature.

HOMER B. EDWARDS.
